HYDRAULIC CLUTCH

Edward W. Smith, Melrose Highlands, Mass., assignor to Vibro Dynamic Engineering, Inc., Boston, Mass., a corporation of Massachusetts

Application May 11, 1948, Serial No. 26,390

5 Claims. (Cl. 74—26)

1

The present invention relates to a coupling unit for the transmission of power and more particularly to such transmission of power in a vibratory system where the unit which is to be ultimately vibrated has a pronounced resonant frequency.

The present invention is more particularly applicable to the transverse vibration of a Four-drinier-wire machine, or to other paper-shaking devices, hat felting machinery, screen vibrations, and to other systems where vibratory energy is applied.

In most of the functions where vibratory energy is applied, a mass is to be vibrated in a vigorous manner and in order to obtain the desired 15 additional amplitude the principle of resonance has been applied.

In the practical application of the use of the principle of resonance to the vibration of a mass, it has been found useful in many instances to couple to the mass to be vibrated another mass through an intervening resilient member so as to form a so-called "two mass" system.

It has also been the practice to supply the necessary vibrational energy to the system by means of an eccentric and an interconnecting shaft to one of the masses since this is a very convenient method of supplying vibrational energy.

Since in starting such a system must of necessity be brought from standstill condition up to the resonant frequency by some method it has been the practice in the past to use, in most instances, an adjustable eccentric whereby the motor driving the eccentric could be brought up to the resonant speed before the amplitude of motion of the eccentric is raised from zero to the desired value. By using this procedure it is thus possible to start the resonant system in vibration at its natural period of vibration.

If this is not done, and the motor is started with the eccentric set at the desired amplitude of vibration at which it is wished to operate, the vibrating system has to pass through the antinode frequency on its way up to the desired frequency. During this period very great demands are made on the eccentric and the motor driving it so that with this procedure in use it is not at all uncommon to find that the size of motor required to bring the system up to speed is several times that required to keep it in operation once the resonant speed is achieved. The necessity for such an uneconomic size of motor can, of course, be eliminated by the use of the adjustable eccentric mentioned above. On the other hand, such eccentrics

are basically rather complicated and expensive so that the cost saved by the ability to use a smaller motor is frequently more than made up for by the cost of the eccentric required.

The present invention was designed to utilize a characteristic of such a two mass system as a basis for a simple and very inexpensive arrangement whereby the motor attached to the simple eccentric may simply be thrown on the line with the eccentric set at the desired operating amplitude and yet without requiring a motor any larger than is required for the running condition.

In accordance with the principles of the present invention the system is entirely automatic and the amplitude will adjust itself to the proper frequency accurately without the necessity of any control whatsoever by the operator. Moreover, the amplitude will at all times conform to the frequency at which the machine is being operated so that it is impossible to overload the driving motor.

The invention will be more fully described in the specification set forth below in connection with the drawings illustrating the system and apparatus in which Figure 1 shows a curve in which the thrust called for is plotted as an ordinate against the vibrating frequency as abscissa for a uniform amplitude of motion. Figure 2 shows the system schematically as a whole to which the invention is applied. Figure 3 shows a cross section through the coupling unit and Figure 4 shows a section taken on a line 4—4 of Figure 3.

Referring to the Figure 1, it will be noted that if we plot thrust on the connecting rod 22, joining the eccentric 2, and one of the masses 3, through the coupling unit 4 against frequency, we have a curve 5, which shows a high thrust required at low frequencies, a high thrust at high frequencies and a minimum thrust at the resonant frequency indicated by line 6 which is normally at the desired operating frequency. Therefore, if we provide, intermediate between the mass and the eccentric, a coupling unit 4 designed so that it will only transmit a fixed amount of thrust without slipping, we can so design it that it will transmit without substantial slip, the thrust required for normal operating loads but any substantial requirement for thrust over and above this amount will result in slippage and thus not exceed the maximum ability of the motor driving the eccentric 2 to deliver it.

The method by which, in the present invention, this result is accomplished is shown schematically

ly in Figure 2, in which the coupling unit 4 controls the amount of thrust which is transmitted.

In Figure 2 the two mass vibrating system which produces the resonance is indicated by the mass 3 and the mass 6. In practice the mass 3 is usually the apparatus itself which is being vibrated. This, for instance, may be the Fourdrinier wire, the materials on the wire, the wire supports, and such other connecting elements to which the spring 7 is attached. Resonance may be established for such a mass unit by the addition of the compensating mass 6, which then establishes a resonant system in which the two masses 3 and 6 are coupled by an elastic element 7. This itself is usual practice and does not per se form a part of the present invention. The coupling unit 4, which is shown more in detail in Figure 3 comprises a shaft or rod 8, which is centrally located within the liquid filled cylinder 9. The rod 8 preferably passes through both ends of the cylinder extending beyond the end wall 10, of the cylinder as indicated at 11. Suitable liquid and fluid tight bearing elements 12 and 13 may be used at each end of the cylinder so that no liquid escapes from within the cylindrical walls. The cylinder is closed at both ends, at the forward end by a cap 14 which may be screwed into the wall of the cylinder or attached in any other means, as, for instance, by a flange, welding, or other suitable manner. The shaft 8 has between its ends within the cylinder a piston 15 with a plurality of fine passages 16 through the piston to permit the desired volume of fluid to flow back and forth between the chambers 17 and 18 formed within the cylinder on either side of the piston wall. The passages 16 may be made in threaded members 19 which thread into the piston wall and are substantially flush with both faces. When it is desired to use passages of larger cross sectional area the thread members 19 may be removed and other threaded members used with the desired passage openings through them. The piston 15 may be welded or fixed in any suitable way to the shaft 8. The piston preferably has a smooth, round fit with the cylinder wall, or such a fit that no fluid or liquid will escape around the piston to the wall edges. Any form of piston may be used and the piston may be provided with suitable piston rings if this proves desirable.

It is preferable, but not necessary in all cases, to carry the shaft 8 through the entire cylinder. By carrying the shaft 8 through the entire cylinder it is possible to have symmetrical chambers 17 and 18 and also to provide a system in which the volumetric changes in the two chambers are proportional to the linear amplitude.

The cylinder 9 may be provided at one end with a yoke 20 to which the mass element 3 may be attached for proper vibration.

The operation of the system and the function of the various elements are described below.

Let us suppose for a moment that the system is at rest and the motor is thrown on the line, the eccentric being set at the desired operating stroke, and that the motor, while able to deliver any normal thrust requirement during the running condition, is nevertheless not able to deliver much more than this.

As soon as the motor starts to rotate it is loaded with thrust required to move the vibrating system at the same amplitude which it is not able to do and therefore the perforated

piston starts to slide inside the cylinder allowing the oil 21 or other liquid used to pass slowly from one side of the piston to the other. Since the perforations offer some resistance to the passage of the liquid the net result is that some thrust is transmitted to the vibrating system 1, although at a lesser amplitude than that of the piston.

Under the above conditions the motor, not being loaded beyond its full load capacity, gradually builds up in speed and at the same time delivers thrust pulsations of the same frequency but at lesser amplitude to the vibrating system. This process continues until the speed of vibration of the vibrating system reaches its resonant value which is assumed to coincide with the maximum speed of the motor under full load. When this condition is reached, as has been seen from Figure 1, the thrust requirement drops to a minimum which is compatible with what the motor can supply without overloading. At the same time, if the perforations in the piston have been so chosen that this amount of thrust is insufficient to drive any substantial amount of oil from one side of the piston to the other, there will be little or no relative motion between the piston and the cylinder and the combination will act substantially as a rigid connection between the eccentric and the vibratory system 1.

In the design of the above transverse hydraulic clutch certain points are to be observed. It has been the inventor's experience that such an oscillatory system as a rough average rule can be assumed to have a Q or amplification of about 10 to 12. Therefore, if the resonant system has such constants for its operating resonant frequency that the maximum force of the spring during vibration is, for instance, 5000 lbs. then the piston-cylinder system should be so designed that at least 500 lbs. of alternating thrust are required to force any appreciable amount of oil from side of the piston to the other, at the frequency used. If this is done the amount of movement of the piston relative to the cylinder will be very little.

While the physical dimensions of the clutch are a matter of design taking into consideration the force to be transmitted and the available space limitations certain factors are of importance and should be taken care of in the design.

First it will be apparent that the larger the diameter of the piston can be consistent with the force to be transmitted the lower the pressure per square inch applied to the piston. This makes possible the use of larger holes in the piston and therefore more manageable ones. It also increases the necessity for extremely tight packing glands to prevent leakage of oil.

Secondly it is desirable that equal motion of the piston in either direction produce equal volume changes in the oil on the two sides of the piston. Thus if the shaft carrying the piston does not extend through both chambers, the amount of motion required to transfer a given amount of oil through the perforations in the piston will vary with the direction of travel of the piston.

Thirdly, if the motion delivered to the clutch is not a pure sinusoid, as can readily be the case where the ratio of offset on the eccentric is not extremely small in relation to the length of the connecting rod, then the inequalities will be taken up in movement of the piston relative to the cylinder even at resonance with a consequent unnecessary power loss and heating of the clutch

to say nothing of probably loss of tight coupling at resonance.

Having now described my invention, I claim:

1. A vibrating system having a resonant vibratable element and a drive element for vibrating the resonant element, a coupling unit comprising an hydraulic cylinder having external means connected to one element of the system and a piston operating therewithin forming fluid chambers on both faces of the piston, said piston having small communicating passages therebetween for the exchange of fluid between chambers and a rod connected to said piston at one end, and at the other end, to the other element of the system.

2. A vibrating system of the type described, comprising an hydraulic coupling unit having a housing forming a piston chamber, a piston positioned within the chamber and adapted to be reciprocated therein, a piston rod attached thereto forming one end of the coupling unit, means attached to the housing forming the other end of the coupling unit, a non-resonant driving system connected to one end of the coupling unit and a resonant driven system connected to the other end of the coupling unit, means forming a communicating passage between the portions of the chamber separated by the piston and fluid means filling the chamber, said piston rod extending through the chamber and projecting at both ends thereof.

3. A vibrating system of the type described, comprising an hydraulic coupling unit having a housing forming a piston chamber, a piston positioned within the chamber and adapted to be reciprocated therein, a piston rod attached thereto forming one end of the coupling unit, means attached to the housing forming the other end of the coupling unit, a non-resonant driving system connected to one end of the coupling unit and a resonant driven system connected to the other end of the coupling unit, means forming a communicating passage between the portions of the chamber separated by the piston and fluid means filling the chamber.

4. A vibrating system of the type described, comprising an hydraulic coupling unit having a housing forming a piston chamber, a piston positioned within the chamber and adapted to be reciprocated therein, a piston rod attached thereto forming one end of the coupling unit, means attached to the housing forming the other end of the coupling unit, a non-resonant driving system connected to one end of the coupling unit and a resonant driven system connected to the other end of the coupling unit, said piston being provided with communicating passages from one face to the other comprising removable plug elements having holes of desired size therethrough, and fluid means filling the chamber and adapted to reciprocate through said passages from one face of the piston to the other.

5. In combination with a driven reciprocating vibrating system having a pronounced resonant frequency of operation, a mechanical driving element, a non-resonant fluid coupling unit connected between the driving and driven element having fluid transfer means operative within the coupling unit for varying the ratio of motional amplitude between the driving and driven elements from off resonance to on resonance of the system for operating the system at minimum thrust irrespective of frequency.
